UNITED STATES PATENT OFFICE.

HORACE T. THOMAS, OF LANSING, MICHIGAN.

CARBURETER.

1,120,763.

Specification of Letters Patent. Patented Dec. 15, 1914.

Application filed October 27, 1909. Serial No. 524,868.

To all whom it may concern:

Be it known that I, HORACE T. THOMAS, a citizen of the United States, residing at Lansing, county of Wayne, State of Michigan, have invented a certain new and useful improvement in Carbureters, and declare the following to be a full, clear, and exact description of the same, such as will enable others skilled in the art to which it pertains 10 to make and use the same, reference being had to the accompanying drawings, which form a part of this specification.

My invention relates to carbureters and has for its object the provision of a carbureter giving a perfect fuel mixture at all 15 practical speeds and climatic conditions. I attain this object in the device illustrated in the accompanying drawings, in which,—

Figure 1, is a central section. Fig. 2, is a detail of the adjustable Venturi tube. Fig. 3, is a detail view of a part of the mechanism for adjusting the Venturi tube. Fig. 4, is a view of the parts shown in Fig. 3, looking from the right of the latter. Fig. 5, 20 is a detail section on the line 5—5, Fig. 1.

A is the reservoir containing the hydrocarbon liquid.

B is a float in the reservoir A.

C is the valve by which the supply of 30 liquid to the reservoir A is regulated through the medium of the float B in any usual way.

D is the supply passage controlled by the valve C.

35 F is a passage leading from the reservoir A, adapted to convey a liquid to a delivery nozzle H having a fixed terminal opening.

G is an air passage in which is located the delivery nozzle H.

40 I is a Venturi tube fitting and adapted to slide in the passage G. The bore of the tube I is of varying diameter, and the delivery opening or mouth of the nozzle H is located in the bore of the tube I. By moving the tube I away from the nozzle H the larger part of the bore is brought adjacent to the delivery opening of said nozzle, and by moving said tube in the other direction the narrower portion of the bore of said tube is 45 brought adjacent to the delivery opening of the nozzle H.

i is a groove formed around the upper edge of the tube I.

50 M is a metal cylinder fitting into a casing N, and extending with its axis at right angles to that of the tube I.

m is a pin extending from the inner end of the cylinder M eccentric to said cylinder, and engaging in the groove i.

b is a slot formed transversely across the cylinder M from its upper surface and near the outer end of said cylinder. The casing N is provided with a slot n in its wall extending in a plane parallel to the axis of said cylinder.

a is a bolt passing from side to side through the casing N and across the slot n, and adapted to draw the sides of the casing N together to clamp the cylinder M in place. The bolt a passes into the slot b, so that the 60 cylinder M is thereby prevented from longitudinal movement.

c is a slot in the outer end of the cylinder M adapted to receive a screw-driver. By turning the cylinder M about its axis the 75 Venturi tube I is adjusted to different positions in the passage G, and may be fixed in its adjusted position by clamping said cylinder in the casing N by means of the bolt a. The air passage G is open to the outer air 80 at its lower end, and at its upper end opens into a chamber g which communicates with a passage P adapted to be connected to the intake of an internal combustion engine.

p is a throttle valve in the passage P. 85

J is an air passage opening at its lower end to the outer air, and at its upper end to the chamber g.

Q is a disk valve normally closing the passage J, and adapted to open into the chamber g.

q is a spring pressing the disk valve Q upon its seat surrounding the entrance from the passage J into the chamber g.

K is a spraying nozzle having a delivery 95 aperture in the passage J, and communicating by a passage k with the reservoir A.

L is a needle valve adapted to control the rate at which liquid passes to the delivery end of the nozzle K.

In carbureters using spraying nozzles, a nozzle having a fixed opening used in conjunction with a surrounding Venturi tube is more sensitive to changes in the speed of the motor than a nozzle of the adjustable 105 needle type. The objection to this fixed opening type of nozzle is that it is not readily adjustable to adapt it to climatic conditions or errors in workmanship. One object of my invention is to provide this adjustment by shifting the position of the Venturi tube relative to the fixed jet, thereby 110

giving the desired regulation, the mechanism not being necessarily as shown in the sketch, but any means whereby this object is accomplished. In order to secure a carbureting device that will produce a perfect mixture at very low motor speeds, it is necessary to have the opening in the Venturi tube surrounding the fuel jet quite restricted, in order that the velocity of air passing may 5 properly break up and vaporize the fuel passing to the jet. I provide, therefore, a fixed-opening jet and the adjustable Venturi tube for closed control work only; the adjustment provided being what is called the closed gate adjustment. That is, the adjustment is that suitable when the throttle or gate valve is nearly closed. As the velocity of the motor increases, due to opening the gate or throttle, a greater proportion 10 of fuel is supplied than required for a perfect mixture. In order to supply the required amount of air, an automatic valve Q is provided, this valve being held to its seat by an adjustable spring q. I thus provide 15 for the proper mixture for medium or ordinary speeds. As the velocity of the motor further increases, the fuel fed by the jet H is inadequate to properly supply the air passing the valve Q. A second jet is 20 therefore provided for by the nozzle K opening into the tube J, this jet being adjustable by the needle valve L. This latter adjustment provides for adapting the apparatus to variations in the tension of the spring 25 q and provides a third adjustment for high

speed or open gate work or for the operation of the engine when the throttle or gate valve is wide open.

Claims:—

1. The combination of a passage G, a 40 Venturi tube adapted to reciprocate in said passage, a fixed delivery nozzle H in said tube, a cylindrical piece M adapted to rotate in a casing N located with its axis at right angles to that of said tube, an eccentric pin m extending from the piece M and engaging said tube, said piece being rotatable about its axis to actuate said tube through said pin, and means for contracting the walls of said casing, for the purpose de- 45 scribed.

2. The combination of a passage G, a Venturi tube adapted to reciprocate in said passage, a fixed delivery nozzle H in said tube, a cylindrical piece M adapted to rotate in a casing N located with its axis at right angles to said tube, an eccentric pin m extending from the piece M and engaging said tube, a bolt for contracting the walls of said casing, for the purpose de- 50 scribed, the piece M being provided with a bolt b, said bolt engaging in the slot in the piece M.

In testimony whereof, I sign this specification in the presence of two witnesses.

HORACE T. THOMAS.
